UNITED STATES PATENT OFFICE.

CARL A. CARLSON, OF EVERETT, MASSACHUSETTS, ASSIGNOR, BY MESNE ASSIGNMENTS, TO THE STAFFORD COMPANY, OF READVILLE, BOSTON, MASSACHUSETTS, A CORPORATION OF MASSACHUSETTS.

WEFT FEELER DEVICE FOR LOOMS.

Application filed May 27, 1919. Serial No. 300,099.

To all whom it may concern:

Be it known that I, CARL A. CARLSON, a citizen of the United States, residing at Everett, in the county of Middlesex, State 5 of Massachusetts, have invented a certain new and useful Improvement in Weft Feeler Devices for Looms, of which the following is a specification, reference being had therein to the accompanying drawings.

10 The invention is an improvement in depletion-detecting and indicating devices, commonly termed weft or filling-feelers, such as are employed in the process of weaving for the purpose of detecting the arrival of a predetermined stage in the progressive depletion of the shuttle-contained supply of weft or filling, and thereupon "indicating" or "calling" a change in the working of the loom prior to complete exhaustion of the said supply, the change "indicated" or "called" involving in some cases 15 automatic weft-replenishment; in other cases, stoppage of the loom.

The invention has relation to side-slipping 20 or "side-swiping" feelers, i. e., the class of depletion-indicating or weft-feeler devices having a feeler-member which is held from movement longitudinally of the shuttle contained filling-carrier through engagement 25 of the shuttle-contained mass of weft or filling with its feeling end, so long as a safe amount of weft or filling remains upon the filling-carrier, and which is caused to shift in the said direction when the remainder of 30 weft or filling is not sufficient to hold it from slipping, in order that thereby the feeler-devices may become operative to call the predetermined change. More particularly, 35 it is an improvement in feeler-devices of such class of the type in which the displacement of the feeler-member longitudinally of the shuttle is caused by pressure against its feeling end.

The invention provides in novel manner 40 for the displacement of the feeler-member longitudinally of the shuttle when the shuttle-contained supply of weft or filling becomes substantially depleted.

Briefly stated, the more characteristic feature of invention consists in the combination 45 with a feeler-member that is adapted to shift sidewise in a horizontal plane lengthwise of the shuttle-contained filling-carrier, of deflector-means movable forward and rearward

in unison with said feeler-member so long 55 as the latter is held from lateral movement, and acting to occasion said lateral movement, when the amount of weft or filling remaining in the shuttle is not sufficient to hold the feeler-member from such movement. 60

The invention finds its preferred embodiment in a feeler-device comprising a laterally-movable feeler-member, a deflector-member, both of which are movable forward and rearward in unison, they respectively 65 having surfaces which are kept in contact with each other by spring-tension, one or both of said surfaces beveled or inclined laterally, means for opposing forward movement of said deflector-member, and controller-devices through which a change in the 70 operation of a loom is called as a result of lateral deflection of the laterally-movable feeler-member. The principle of the mode of operation of this form of embodiment is 75 that so long as the weft or filling that is pressed against the tip of the feeler-member in a feeling action holds the feeler-member from movement longitudinally of the shuttle contained filling-carrier the two members 80 simply are pushed forward in unison, without slipping of the said surfaces upon each other, but when the amount of weft or filling upon the filling-carrier is not sufficient to hold the feeler-member against tendency 85 to lateral deflection, its surface slips along that of the deflector-member and the bevel or incline produces movement of the feeler-member longitudinally of the shuttle, so that the feeler-mechanism is rendered operative 90 to call the predetermined result in the working of the loom.

Fig. 1 of the drawings is a plan view of 95 feeler-devices embodying the invention, combined with controller-mechanism, and portions of a loom, including a shuttle containing a bobbin loaded with weft or filling.

Fig. 2 is an end elevation of the feeler-devices and controller-mechanism of Fig. 1.

Fig. 3 is a plan view of the said feeler-devices and a part of the controller, illustrating 100 a feeling-action at the full-diameter stage of the weft or filling occupying the shuttle.

Fig. 4 is a like-view illustrating the action 105 when the depleted state of the weft or filling leads to side-slipping of the feeler-member.

Referring to the illustrated embodiment of the invention:

At 1 is the feeler-member, it having its tip 1^a serrated as usual in feeler-devices of the side-slipping type. The forward portion of its stem 1^b occupies loosely a guide constituted by a hole in a portion 2^a of the stand 2, and slides through said hole as the feeler-member reciprocates lengthwise, the loose fit of the stem within the hole rendering the feeler-member able to swing transversely at the rear of said guide-portion 2^a when the tip 1^a slips sidewise upon the shuttle-contained weft-carrier 10 in a feeling-action as in Fig. 4. The transversely-swinging feeler-member is supported at the rear of portion 2^a of the stand by a guide constituted by the top surface of a transverse portion 2^b of the stand, and is adapted 20 to slide thereon forward and rearward as well as sidewise.

At 3 is a slide which is fitted to guides at 4^a, 4^b, in connection with stand 2, in which it is adapted to move lengthwise toward and 25 from the lay, its stem being surrounded by an expanding spiral spring 5 confined between the guide 4^a and a shoulder 3^a that is formed at the point where the said stem joins the body-portion of the deflector-member, and said spring tending to keep the slide 3 in its rearward position, which latter is determined by contact of its stops 3^b, 3^b, with the front of guide 4^b.

The slide 3 is formed at the side thereof 35 next the feeler-member with a beveled surface *a* that inclines forwardly, and the feeler-member is formed at the side thereof next the slide 3 with a counterpart or reverse beveled surface *b*. These two beveled 40 surfaces are kept pressed together by spring-tension, the latter being applied by means of an expanding spiral spring 6 encircling a transverse rod 7 which is connected with the feeler-member by a pivot at 8. The 45 rod 7 extends transversely outward from the feeler-member through a hole in the slide 3, the spring 6 being confined between the outer side of the slide 3 and a head or collar 9 upon the outer end of the rod.

50 In operation, so long as there remains upon the weft or filling-carrier 10 occupying the shuttle 11 upon the lay 12 a sufficient quantity of weft or filling to hold the feeler-member from moving sidewise, longitudinally of the shuttle, at the time of a feeling action (see Fig. 3), the feeler-member is pushed straight forward by the pressure of the filling-mass against its tip, and it drives the slide 3 forward also, overcoming 55 the resistance of spring 5. In this action, the side lug 1^c projecting inwardly from the feeler-member passes forward alongside the slide-bar 10, without changing the position of said slide-bar. When, however, in a feeling-action the feeler-member is caused to

slip sidewise as in Fig. 4, the sidewise movement thereof carries the side-lug 1^c thereof into position to engage with the slide-bar 10, so that as the laterally-shifted feeler-member 3 goes forward it takes the slide-bar 10 with it. The slide-bar 10 is arranged to move longitudinally within holes in the portions 2^a, 2^b, of the stand 2. In the rearward position of the said slide-bar, a block 10^a thereon supports the arm 11 of the controller, 75 as in Fig. 3. When the slide-bar is driven forward in the manner shown by Fig. 4, this block is moved out from under the arm 11 so that the controller is free to turn to call a change in the working of the loom in connection with which the feeler-device is employed. The controller and the parts which it controls are as usual. In the present instance the controller and its connections are such as are in general use for calling or 85 bringing about automatic replenishment of filling. An expanding spiral spring 12, confined between the portion 2^a of stand 2 and a collar 10^b upon slide-bar 10 returns the slide-bar rearwardly to its normal position 90 shown in Figs. 1 and 3, the rearward movement being limited by contact of a stop-nut 10^c, that is carried by the front end of the slide-bar, with the front side of guide-portion 2^a. 95

What I claim is:

1. A weft or filling-feeler for looms, comprising a laterally-movable feeler-member, a deflector-member, both thereof movable forward and rearward in unison, they respectively having surfaces which are kept in contact with each other by spring-tension and one or both of said surfaces beveled or inclined laterally, means for opposing forward movement of said deflector-member, 100 and controller-devices through which a change in the operation of a loom is called as a result of lateral deflection of the laterally-movable feeler-member.

2. In weft or filling feeler-devices of the side-slipping class, the combination with a feeler-member that is adapted to shift sidewise in a horizontal plane lengthwise of the shuttle-contained filling-carrier, and a controller through which the change is called 110 as a result of transverse shift of the feeler-member in a feeling action, of a yielding deflector movable forward and rearward in company with the feeler-member which tends to deflect the feeler-member sidewise 115 by cam-action and which effects the said shift when the weft or filling remaining on the shuttle-contained filling-carrier is no longer sufficient to hold the feeler-member from slipping sidewise along the filling-carrier. 120

3. A weft or filling-feeler for looms comprising, in combination, a feeler-member 1 having a beveled surface and an engaging lug or projection, guides permitting longi- 130

tudinal and side-slipping movements of said feeler-member, a spring-actuated slide having a beveled surface coacting with the said surface of the feeler-member, a spring operating to press the feeler-member toward the slide, a slide-bar adapted to be actuated by the said lug or projection, and a controller controlled by the said slide-bar.

4. In a feeler mechanism for looms, the combination of a feeler and a deflector each mounted for movement toward and from the front of the loom, one of said members having an inclined surface which is engaged by the other member and tends to move the feeler laterally under the frontward pressure against the feeler on a detecting beat to effect replenishment of filling and is prevented from effecting such lateral movement by engagement of the feeler with the filling until substantial exhaustion thereof, and means connected to the feeler for effecting replenishment of filling.

5. In a feeler mechanism for looms, the combination of a feeler which is mounted for movement toward the front of the loom on each detecting beat regardless of the amount of filling in the shuttle, a deflector, means for independently supporting the deflector and feeler, interengaging inclined parts between the feeler and deflector which tend to effect movement of the feeler longitudinally along the filling carrier on each detecting beat and which are prevented from effecting such movement of the feeler by engagement of the feeler with the filling on each detecting beat until substantial exhaustion of the filling.

6. In a feeler mechanism for looms, the combination of a feeler mounted for frontward and lateral movements, a deflector mounted for frontward movement and having a laterally inclined portion which crosses a portion of the feeler when the latter is in normal position, and a part carried by the feeler which bears upon said inclined portion of the deflector as the feeler is pushed frontwardly on a detecting beat and which tends to impart lateral movement to the feeler and effect such lateral movement when the filling is substantially exhausted on a detecting beat.

7. In a feeler mechanism for looms, the combination of a feeler which is mounted for movement toward and from the front of the loom on each detecting beat regardless of the amount of filling on the filling carrier in the shuttle, a deflector, interengaging cam portions on the feeler and deflector which, under the frontward pressure on a detecting beat, tend to cause the feeler to move along the filling carrier to effect replenishment of filling, but are prevented from effecting such movement until the filling is substantially exhausted, and means for effecting replenishment of filling when

the deflector succeeds in moving the feeler along the filling carrier.

8. In a feeler mechanism for looms, the combination of a feeler which is mounted for movement toward and from the front of the loom on each detecting beat regardless of the amount of filling on the filling carrier in the shuttle, a deflector, interengaging cam portions on the feeler and deflector which, under the frontward pressure on a detecting beat, tend to cause the feeler to move along the filling carrier to effect replenishment of filling, but are prevented from effecting such movement until the filling is substantially exhausted, means for limiting the amplitude of movement effected by the cam portions, and means for effecting replenishment of filling when the deflector succeeds in moving the feeler along the filling carrier.

9. In a feeler mechanism for looms, a feeler mounted for movement toward and from the front of the loom and in a direction longitudinally of the shuttle but held from such longitudinal movement by engagement with the filling on a detecting beat until substantial exhaustion thereof, a companion member mounted for movement toward and from the front of the loom, a cooperating cam and recess, one on the feeler and the other on the companion member for causing frontward movement of the feeler to move the said member frontwardly without relative frontward movement of the two when a working supply of filling is present on a detecting beat and for causing the feeler to move laterally away from the companion member when filling is substantially exhausted, means for limiting the movement of the feeler away from the companion member, and yielding means tending to hold the cam and recess in engagement.

10. In a feeler mechanism for looms, the combination of a feeler, a companion member yieldingly held in rearward position and extending alongside the feeler, engaged inclines on the feeler and companion member for moving the feeler away from the said member and in a direction longitudinally of the shuttle by the frontward push upon the feeler on a detecting beat and held from effecting such movement by engagement of the feeler with the filling until substantial exhaustion thereof, means extending between the feeler and companion member to limit the movement of the feeler away from the said member, and means for replenishing filling when the feeler is moved longitudinally of the shuttle.

11. In a feeler mechanism for looms, the combination of a feeler, a companion member extending alongside the feeler, a spring acting rearwardly upon said member, inclines on the feeler and companion member which cause the two to be moved frontwardly in unison by the push against the feeler

on a detecting beat when a working supply of filling is present and which cause movement of the feeler relative to the companion member in a direction longitudinally of the shuttle by the forward push upon the feeler when the filling is substantially exhausted, and a member moved by the feeler when filling is substantially exhausted to effect replenishment of filling.

10 12. In a feeler mechanism for looms, the combination of a feeler, a companion member extending alongside the feeler, cam connections between the feeler and companion member, yielding means for holding the cam 15 connections in engagement, and a single spring acting upon the said member for holding both the latter and the feeler in rearward position.

13. In a feeler mechanism for looms, the combination of a filling engaging feeler mounted for movement toward and from the front of the loom and longitudinally of the shuttle, a companion member mounted for movement toward and from the front of 25 the loom and extending in the general direction in which it moves substantially parallel with the feeler, means for yieldingly forcing the said member rearwardly, and connections between the feeler and such member 30 constructed and arranged to move the feeler away from the companion member in a direction longitudinally of the shuttle when the feeler is moved forwardly by the forward push of a surface within the shuttle 35 and is not held from moving longitudinally of the shuttle by the filling.

14. In a feeler mechanism for looms, the combination of a feeler, a companion member extending alongside the feeler and 40 mounted for movement toward and from the front of the loom, connections between the feeler and said member for causing both the feeler and the companion member to be moved forwardly by the push upon the 45 feeler when a working supply of filling is present in the shuttle on a detecting beat and for causing movement of the feeler in a direction longitudinally of the shuttle by the forward push of a surface within the 50 shuttle when the filling is substantially exhausted, and a spring for holding the connections in yielding engagement.

15. In a feeler mechanism for looms, a feeler guide mounted for movement toward 55 and from the front of the loom, a feeler lying alongside the feeler guide, and mounted for movement toward and from the front of the loom and in a direction longitudinally of the shuttle but held from such longitudinal movement by engagement with the filling on a detecting beat until substantial exhaustion thereof, a cooperating cam and recess, one on the feeler and the other on the feeler guide for causing frontward 60 movement of the feeler to move the guide

frontwardly without relative frontward movement of the two when a working supply of filling is present on a detecting beat and for causing the feeler to move laterally away from the feeler guide when filling is 70 substantially exhausted, a stop for limiting the movement of the feeler away from the feeler guide and yielding means tending to hold the cam and recess in engagement.

16. In a feeler mechanism for looms, the combination of a feeler guide yieldingly held in rearward position, a feeler extending alongside the feeler guide, engaged inclines on the feeler guide and feeler for moving the latter away from the former and in a 80 direction longitudinally of the shuttle by the forward push upon the feeler on a detecting beat and held from effecting such movement by engagement of the feeler with the filling until substantial exhaustion thereof, means extending between the feeler and feeler guide to limit the movement of the feeler away from the feeler guide and means for replenishing filling when the feeler is moved longitudinally of the shuttle. 90

17. In a feeler mechanism for looms, the combination of a feeler guide, a spring acting rearwardly upon said guide, a feeler extending alongside the feeler guide, inclines on the feeler guide and feeler which 95 cause the two to be moved forwardly by the push against the feeler on a detecting beat when a working supply of filling is present and which cause movement of the feeler relative to the feeler guide in a direction longitudinally of the shuttle by the frontward push upon the feeler when the filling is substantially exhausted, a member adjacent the feeler and moved by the feeler when filling is substantially exhausted to 105 effect replenishment of filling.

18. In a feeler mechanism for looms, the combination of a feeler guide, a feeler having a portion extending alongside the feeler guide, cam connections between the feeler guide and said portion, yielding means for holding the cam connections in engagement, and a single spring acting upon the feeler guide for holding both the feeler guide and feeler in rearward position. 110

19. In a feeler mechanism for looms, the combination of a feeler guide mounted for movement toward and from the front of the loom and extending in the general direction in which it moves, a filling engaging feeler 120 extending substantially parallel to the feeler guide and mounted for movement toward and from the front of the loom and longitudinally of the shuttle, means for yieldingly forcing the feeler guide rearwardly, 125 and connections between the feeler guide and feeler constructed and arranged to move the feeler away from the feeler guide in a direction longitudinally of the shuttle when the feeler is moved forwardly by the front- 130

ward push of a surface within the shuttle and is not held from moving longitudinally of the shuttle by the filling.

20. In a feeler mechanism for looms, the combination of a feeler guide mounted for movement toward and from the front of the loom, a feeler having a portion extending alongside the feeler guide, connections between the feeler guide and said feeler portion for causing both the feeler and feeler guide to be moved frontwardly by the push upon the feeler when a working supply of filling is present in the shuttle on a detecting

beat and for causing movement of the feeler in a direction longitudinally of the shuttle 15 by the frontward push of a surface within the shuttle when the filling is substantially exhausted, and a spring for holding the connections in yielding engagement.

In testimony whereof I affix my signature 20 in presence of two witnesses.

CARL A. CARLSON.
